(57) **CLAIM**

The ornamental design for an upper housing assembly for supercharger, as shown and described.

DESCRIPTION

FIG. 1 is a top perspective view of an upper housing assembly for supercharger according to the present invention;

FIG. 2 is a bottom perspective view of the upper housing assembly for supercharger according to the present invention;

FIG. 3 is a top view thereof;

FIG. 4 is a front view thereof;

FIG. 5 is a bottom view thereof;

FIG. 6 is a rear view thereof;

FIG. 7 is a right side view thereof; and,

FIG. 8 is a left side view thereof.

The broken lines shown in the drawings illustrate environmental features and form no part of the claimed design.
